UNITED STATES PATENT OFFICE.

IRA L. GLEASON, OF MILWAUKIE, OREGON.

TOY WAGON.

Application filed June 14, 1922. Serial No. 568,293.

To all whom it may concern:

Be it known that I, IRA L. GLEASON, a citizen of the United States, and a resident of Milwaukie, county of Clackamas, and 5 State of Oregon, have invented a certain new and useful Improvement in Toy Wagons, of which the following is a specification.

The object of my invention is to provide a toy wagon which may be pulled along by its 10 tongue, and with the latter so constructed that it may be arranged to serve as steering means for the wagon when it is to be used as a coaster. In other words the tongue is so constructed that it can be extended 15 and be used as a tongue to draw the toy. It may be locked extended and upright and the wagon can be used as a pushmobile, or it may be extended upright and broken in the center and extended backward and the 20 wagon can be used as a coaster. In the latter position a brake can also be used and provide an efficient means for stopping the momentum of the coaster.

A further object is to provide a toy which 25 is rigidly and substantially built and in which the hinged and pivoted parts are designed to withstand considerable rough usage.

These and other objects I have illustrated 30 in the accompanying drawings, in which:

Fig. 1 is a side elevation of my device showing the handle extended and arranged angularly so as to be used as a coaster;

Fig. 2 is a partial front view of my convertible handle;

Fig. 3 is a section taken on the line 3—3 of Fig. 1 and shows the rear construction of my device;

Fig. 4 is a perspective view of the member 40 which constitutes the brake element;

Fig. 5 is an elevation of the adjustable handle of my toy and shows it extended for use as a tongue and shows how it can be arranged angularly and locked in upright 45 position;

Fig. 6 is a perspective view of the construction of the support by which my convertible handle is attached to my device;

Fig. 7 is a fragmentary perspective view 50 showing the construction of the tail gate of my device; and

Fig. 8 is a perspective view of the brace which secures the steering handle in angular 55 position with the tongue.

My device consists of a body *a*, a pivoted wheel *b*, two fixed rear wheels *c*. The body

is made with side boards *d* and a hinged tail gate *e*. The braces *f* connect with the body *a* and the rear axle *g* and serve to form a rigid structure. The body is cut away as at 60 *h* so as to allow the child operating the toy to sit between the side boards *d* and place its feet on the brake *i*. The brake *i* is hinged as at *j* and can be normally held off the ground by the clamping piece *k*. The forked 65 member *l* is pivotally mounted on the body *a* by the bracket *m* thru the U-shaped member *n* and the bolt *n'*. The wheel *b* is mounted between the forked end of the member *l*. The tongue *o* by which my toy can 70 be drawn or steered is pivotally mounted to the bracket *l* as at *p*.

The handle *o* is hinged at its middle as at *q* so that the upper part *o'* constituting a steering handle, can be bent backward over 75 the wagon. The brace *r* is fastened to the handle *o* and the offset clip *s* is fastened to the steering handle *o'*. When the steering handle *o'* is extended backward so as to be in angular position with the tongue the 80 brace *r* can be extended and fitted under the clip and thus forms a saddle, thus providing a firm substantial rest for this extended piece. This forms a rigid structure whereby a child coasting would have complete control at all times.

The cross-bar *t* is seated in the handle *o'* near the end and provides a two-handed grip for the child to enable it to steer the vehicle. When the tongue is extended so that the 90 section *o'* forms a continuation of the tongue *o*, the channeled section *u* is adapted to fit about the tongue *o* and the pivoted offset clamp *v* can be forced over the channel section *u* and thus interlock the two sections. 95 The brace *r* can be dropped to its downward position and the handle is rigid as if of one section.

Thus when the handle is extended it can be used as a draw bar or else the retaining 100 band *w*, pivotally connected to the tongue *o*, can be placed over the forked member *l* and the handle will be locked in upright position. The ends of the handle and the forked member are cut diagonally. When 105 the tongue and steering handle are disposed angularly with each other and the clamp *v* released, the upper section *o'* can be bent over so that it will lie along the tongue. The ends of the handle and the forked 110 member will fit together and when the retaining band is fitted over the forked mem-

2
ber the handle is securely locked upright in place. The crosspiece *t* is then close to the body of the wagon and provides a convenient grip for a child who is lying flat 5 on the wagon, coasting. The tail gate *e* is hinged as at *y* and removably held in its closed position by the hook *z*. If a child wants to lie flat on the wagon and coast, the tail gate *e* can be dropped and the child 10 can lie between the side pieces *d*. The drag brake *i* is positioned preferably adjacent the front wheel and spaced so that a child seated on the wagon can brace itself against the tail gate when applying pressure on this 15 brake. The brake hangs pendent and slightly behind perpendicular when it is released from the clamps *k* and thus as force is applied against it to stop the wagon, the friction will increase in relation to the 20 pressure applied, and if applied sufficiently the front wheel of the wagon will be forced off the ground and the front part will rest entirely on the brake. It has been found in toy wagon construction that a brake applied 25 to the wheel is not effectual because it does not result in a sufficient sudden stop. This is because sufficient pressure could not be obtained thereon. By using this brake a child can stop the coasting wagon very 30 quickly and when the brake becomes worn a new board can be placed in the bracket holding it, very cheaply.

I have adapted my coaster wagon so that it can be used in many different ways and 35 combines practically all types of coaster wagons now in use, merely by changing the position of the handle and allowing the occupant to ride in any position. If it is desired to draw the wagon along using the 40 handle as a draw bar the steering handle can be extended from the tongue and form one continuous handle. The tongue being fixed to the steering wheel allows the wagon to be guided in any desired direction. If 45 the occupant desires to place one knee on the wagon and propel the toy along with the other leg the handle can be broken as shown in Fig. 1 and braced by the member *r* and the handle can be grasped by the 50 cross-bar *t* and can be thus steered effectively. If the child desires to sit down in the wagon the handle is left the same and the feet can be placed on the brake *i*, the wagon bed being narrow at *h* so as to allow 55 the feet to be comfortably placed on the brake. If the child desires to lie flat the tail gate *e* can be dropped and the occupant can double the handle back on the tongue and lock it in position by means of 60 the retaining band *w* and the cross-bar *t* is therefore close to the wagon bed and positioned so as to form an efficient steering device.

I claim:

65 1. In a toy wagon, a steering wheel hay-

ing an upright steering post, a tongue hinged to the steering post, adapted for being placed in upright position, a steering handle hinged to the extremity of the tongue, for folding against the latter, a 70 cross-bar provided on the outer end of the steering handle, means for securing said steering handle in alinement with the tongue, means for securing the tongue in upright position to the steering post, said 75 means also being adapted to secure the steering handle folded against the tongue, thereby bringing said cross-bar nearer the wagon bed.

2. In a toy wagon, a steering wheel having 80 an upright steering post, a tongue hinged to the steering post, adapted for being placed in upright position, a steering handle hinged to the extremity of the tongue, for folding against the latter, a cross-bar provided on 85 the outer end of the steering handle, means for securing said steering handle in alinement with the tongue, means for securing the tongue in upright position to the steering post, and a brace pivotally attached to said 90 tongue, adapted to hold the steering handle in angular position with the tongue.

3. In a toy wagon, a steering wheel having 95 an upright steering post, a tongue hinged to the steering post, adapted for being placed in upright position, a steering handle hinged to the extremity of the tongue, for folding against the latter, a cross-bar provided on 100 the outer end of the steering handle, means for securing said steering handle in alinement with the tongue, means for securing the tongue in upright position to the steering post, and a brace pivotally attached to said 105 tongue, adapted to hold the steering handle in angular position with the tongue, the extremity of the brace being formed to constitute a saddle in which the steering handle is seated.

4. In a toy wagon, a steering wheel having 110 an upright steering post, a tongue hinged to the steering post, adapted for being placed in upright position, a steering handle hinged to the extremity of the tongue, for folding against the latter, a cross-bar provided on 115 the outer end of the steering handle, means for securing said steering handle in alinement with the tongue, means for securing the tongue in upright position to the steering post, a plate fastened to the under side of the steering handle, such plate having an offset portion constituting a socket, a brace hinged to the tongue adapted to be seated in said socket at its 120 free end thereby to hold the steering handle in angular position with the tongue, the extremity of the brace being formed to 125 constitute a saddle in which said steering handle is seated.

5. In a toy wagon, a steering wheel having 130 an upright steering post, a tongue hinged

to the steering post at a point below its upper end, a steering handle hinged to the extremity of said tongue and adapted to be folded back against the latter, a retaining band pivotally attached to said tongue and adapted to fit over said steering post when said tongue is in upright position, thus securing said tongue to said steering post, the top of said steering post and the extremity of said steering handle having co-operating flanges which engage when the steering handle is folded against the tongue and when the tongue is secured to the steering post, the retaining band thus locking the tongue to the steering post as well as holding the handle folded against the tongue.

6. In a toy wagon, a steering wheel having an upright steering post, a tongue hinged to the steering post, a steering handle hinged to the extremity of said tongue and adapted to be folded back against the latter, a channel section adapted for securing the said steering handle in alinement with the tongue, a retaining band pivotally attached to said tongue and adapted to fit over said steering

post when said tongue is in upright position, thus securing said tongue to said steering post.

7. In a toy wagon, a steering wheel having an upright steering post, a tongue hinged to the steering post at a point below its upper end, a steering handle hinged to the extremity of said tongue and adapted to be folded back against the latter, a cross-bar provided on the outer end of the steering handle, a retaining band pivotally attached to said tongue and adapted to fit over said steering post when said tongue is in upright position, thus securing said tongue to said steering post, the top of said steering post and the extremity of said steering handle having co-operating flanges which engage when the steering handle is folded against the tongue and when the tongue is secured to the steering post, the retaining band thus locking the tongue to the steering post as well as holding the handle folded against the tongue.

IRA L. GLEASON.
